(57) **CLAIM**

The ornamental design for a first aid case, as shown and described.

DESCRIPTION

FIG. 1 is a perspective view of the first aid case;

FIG. 2 is a second perspective view of the first aid case;

FIG. 3 is a top view of the first aid case;

FIG. 4 is a front view of the first aid case;

FIG. 5 is a rear view of the first aid case;

FIG. 6 is a bottom view of the first aid case;

FIG. 7 is an end view of the first aid case; and,

FIG. 8 is a second end view of the first aid case.

The broken lines in FIGS. 1-7 disclose an enlarged view of the surface texture of the case. This surface texture covers the entire case.
